UNITED STATES PATENT OFFICE.

JOSEPH P. ECK, OF MUNCIE, INDIANA.

ELECTRICAL APPARATUS FOR CHARGING FURNACES.

SPECIFICATION forming part of Letters Patent No. 605,090, dated June 7, 1898.

Application filed August 12, 1897. Serial No. 648,000. (No model.)

To all whom it may concern:

Be it known that I, JOSEPH P. ECK, a citizen of the United States, residing at Muncie, in the county of Delaware and State of Indiana, 5 have invented a certain new and useful Improvement in Electrical Apparatus for Charging Furnaces and the Like, of which the following is a specification.

My present invention relates to a new and 10 useful improvement in electrical apparatus for charging furnaces, and especially those known as "open-hearth" furnaces, with scrap or other iron, and has for its object to provide a simple and effective device for bringing about the several operations necessary to 15 perform the desired function by a series of electrical motors, which are put under easy control of the operator, who stands upon a platform carried by the traveling crane or 20 charging-frame.

With these ends in view this invention consists in the details of construction and combination of elements hereinafter set forth and then specifically designated by the claims.

25 In order that those skilled in the art to which this invention appertains may understand how to make and use the same, the construction and operation will now be described in detail, referring to the accompanying drawings, forming a part of this specification, in which—

Figure 1 is an elevation of an apparatus made in accordance with my improvement, the stationary supporting-tracks being in section 35 and a portion of the furnace also being shown in section, the charger-bar having a suitable pan supported thereon; Fig. 2, a section at the line $x-x$ of Fig. 1, showing the mechanism for operating the traveling crane as well as 40 elevating the movable bearing of the charger-bar, whereby the outer end thereof may be brought into proper alignment with the furnace-door; Fig. 3, a section at the line $y-y$ of Fig. 2; Fig. 4, a section of a portion of the 45 traveling crane, taken longitudinally through the charger-bar, showing the interior thereof, and a cam-rod for locking the charging-pan to the outer end of this bar; Fig. 5, a plan view of the charger-tracks and truck-frame to 50 adapted to run thereon, and also the mechanism for causing the charger-truck tracks to

move upon the supporting-tracks, so as to bring the charger in its proper position relative to the various doors of the furnace; Fig. 6, an enlarged section at the line $z-z$, showing the 55 oscillating casting and roller bearing through which the charger-bar passes; Fig. 7, an enlarged section of the outer end of the charger-bar, illustrating the locking-cam holding the 60 pan in position; and Fig. 8, a cross-section of the outer end of the charger-bar upon a line with this cam, the cam being turned upward in its locking position.

In carrying out my invention as here embodied, K is a track running upon a runway 65 L for carrying an electric crane. Each end of track K is carried upon a truck P. The machinery for driving these trucks consists of a motor M and spur-wheels located at 9 or the back end of track K. The trucks are 70 connected by a shaft K', running the full length of the track. This track may be carried from one end of the runway to the other by means of this gearing. Upon the track K is located a charger-truck frame A' and A². 75

D is the motor for driving the charger-truck carrying the load into the furnace and withdrawing the charging-bar.

The spur-wheels D' and D² are connected to the shaft of the charger-truck. Spur-wheel D² is made fast to the front axle of the 80 charger-truck and turns the flange-wheels D³.

B is a hollow shaft used as a charging-bar. Within this shaft is a small shaft or rod C, on one end of which is made fast a hand-wheel 85 O. At the other end is an eccentric cam C', which by turning the hand-wheel O is turned within the shaft or extended through a notch in the wall of the shaft at the top, as shown in Fig. 7. 90

G represents the charging-pan, upon the back end of which is a large casting, as shown. In this casting is a square hole with a notch at the back end, which cam C is made to enter by means of the hand-wheel O after the 95 charging-bar is entered into the square hole. This locks the charging-pan upon the charging-bar securely, so that it may not be drawn off and left in the furnace.

The charging-bar is supported at B' by a 100 casting H, which is pivoted in casting I, and casting I is bolted securely to A². The charg-

ing-bar is made to turn on pin-bearings X, X being a bearing similar to X' and located at 7. On the back end of the charging-bar B is keyed a worm - wheel J for turning the 5 charging-bar. Meshing into J is a screw T, and T is turned with a shaft by motor F, which is located upon a bracket bolted to the carrier U. Carrier U has a wide pin-bearing and shelf for motor F, and motor F lowers 10 and raises with carrier U, and the connecting-wire is so coiled from the controller to motor as to hang loose. Carrier U is made to move up and down in slide U' by means of the shafts R, the upper ends of which are 15 threaded.

Motor E operates a shaft upon which is keyed two screws Y. These screws mesh into worm - wheels V, which are screwed upon shafts R and held in place by brackets, as 20 shown in Fig. 2. This gearing raises and lowers the back end of the charging-bar B, tilting the pan up or down.

N represents electric controllers.

1 and 2 are field-wires stretched along one 25 girder of the runway. A bracket-trolley supported from the truck P furnishes contact with these field-wires. 3 and 4 represent a second pair of field-wires strung along the charger-track. 5 and 6 represent another 30 pair of field-wires also upon the charger-track. These are connected to the switchboard at A³ and furnish current for motors D, E, F, and M, and this switchboard is for the purpose of 35 making or breaking all of the currents from the controllers to the motors, so as to throw the current off when the apparatus is out of use.

Z represents a platform to accommodate the operator, and upon this platform are located 40 the controllers N, here shown as four in number, one for each motor, in order that the entire operations of the device may be under the immediate control of the operator standing upon the platform.

45 It is obvious that this immediate charger may be utilized in conjunction with a number of furnaces, the only requirement being that all of said furnaces are in a line in order that the charger-track may be brought into proper 50 alinement with the doors thereof.

Having thus fully described my invention, what I claim as new and useful is—

1. A furnace-charging apparatus consisting of a charger-track adapted to travel across the 55 face of the furnace, a charger-frame adapted to run upon said track, a charger-bar pivotally suspended within said frame, a rod rotatable in the charging-bar, a cam adapted to enter the wall of the charging-bar and engage 60 the shank of the pan, means for raising and lowering the outer end of said charger-bar, and suitable electric motors in proper circuit for operating the various parts of the apparatus, as specified.

65 2. In combination, supporting-tracks arranged parallel with the front of the furnace, a charger-track mounted upon trucks adapted

to travel upon said supporting-tracks, a charger-frame, a truck from which said frame is suspended, said truck being adapted to run 70 upon the charger-track, a casting suitably pivoted within the charger-frame, a charger-bar journaled within said pivoted casting, a vertically-movable casting fitted to slide within the charger-frame, and through which the 75 charger-bar passes, and mechanism for revolving the charger-bar, an electric motor for operating said mechanism, and an electric motor for causing the charger-truck to travel upon its track, and an electric motor for 80 causing the charger-track to move to and fro upon the supporting-track, as specified.

3. In combination with a charging apparatus, two charging-tracks, two trucks adapted to run thereon, a shaft for connecting the 85 trucks, a hollow charging-bar, an operating-rod journaled in the ends of the charging-bar, a cam formed at one end of the operating-rod adapted to engage the shank of the charging-pan, substantially as described. 90

4. In combination with a traveling charger-track of the character described, a truck adapted to run thereon, an electric motor carried by said truck, suitable gearing connecting the wheels of said truck with said motor, 95 a trolley carried by the truck and adapted to travel upon suitable line-wires for transmitting an electric current to and from said motor, a charger-frame depending from the truck, a casting pivoted within the frame, a 100 hollow charging-bar journaled within said pivoted casting, a vertical movable casting in which the rear end of the charger-bar is journaled, suitable mechanism for raising and lowering said casting, an electric motor for 105 operating said mechanism, a trolley carried by the charger-frame for transmitting an electric current from suitable line-wires, and a platform containing the controller and switchboards upon which the operator may stand 110 for bringing about the proper movements of the charger, substantially as shown and described.

5. In combination with a charger-frame of the character described, a casting pivoted to 115 said frame, a hollow charger-bar journaled in said pivoted casting, a vertical movable frame fitted to slide within the charger-frame and in which the rear end of the charger-bar is journaled, suitable mechanism for raising 120 and lowering said frame, an electric motor carried by the charger-frame for operating this last-named mechanism, suitable gearing connected with the charger-bar for turning the same upon its axis, an electric motor suitably mounted for operating this gearing, suitable trolleys for transmitting an electric current from line-wires to the motors, a cam-rod 125 journaled within the hollow charging-bar, a cam carried upon the inner end thereof adapted to enter into engagement with the shank of the charging-pan, thereby locking the same upon the charger-bar, a hand-wheel upon the outer end of the cam-rod for manipulating 130

the same, and a platform upon which the operator may stand, for controlling the movements of the apparatus, as specified.

6. In combination with a charger-frame of the character described, a charger-bar pivotally attached thereto, mechanism for raising and lowering the outer end thereof, mechanism for turning said charger-bar upon its axis, a charger-pan with which the outer end of the charger-bar is adapted to engage, a rod journaled within the hollow charger-bar, a cam carried upon the inner end thereof and adapted to enter into engagement with the shank of the charging-pan for locking the same upon the charger-bar, and means for bringing about the several movements of the charger-bar, as shown and described.

7. In combination with a hollow charging-bar of the character described, a rod jour-

naled therein, a cam carried upon the inner end of said rod and adapted to be turned upward through an opening in said bar, a hand-wheel for manipulating said rod, and a charging-pan having a shank in which is formed a square hole for the entrance of the square end of the charger-bar and also having a notch formed therein, with which the cam may engage for locking the pan upon the charger-bar, substantially as and for the purpose set forth.

In testimony whereof I have hereunto affixed my signature in the presence of two subscribing witnesses.

JOSEPH P. ECK.
